UNITED STATES PATENT OFFICE.

THOMAS JAMES TAPLIN, JR., OF LONDON, ENGLAND.

STABILIZER FOR AEROPLANES.

1,315,647.

Specification of Letters Patent.

Patented Sept. 9, 1919.

Application filed March 4, 1919. Serial No. 280,514.

To all whom it may concern:

Be it known that I, THOMAS JAMES TAPLIN, Jr., a subject of the King of England, residing in London, England, have invented 5 certain new and useful Improvements in Stabilizers for Aeroplanes, of which the following is a specification.

This invention is for improvements in or relating to stabilizers for aeroplanes, and 10 has for its object to provide a simple device operated by wind-pressure for effecting the required stabilization.

It has before been proposed to use a pendulum for this purpose, but according to the 15 present invention, there is combined with an automatic control-stick carried by a universal joint near one end and having a four-way vane at the other, the blades of which are disposed in vertical planes two pointing 20 fore and aft and the other two to opposite sides of the machine, two lateral springs which tend to keep the stick upright in a plane transverse to the direction of movement of the machine, two springs or a spring 25 and a stop which tend to keep the stick upright in a vertical plane which is parallel to the direction of travel, means for operatively connecting the stick to the elevator to control the latter by fore and aft movements, 30 and means for operatively connecting the stick to the ailerons for controlling the same by lateral movements of the stick.

According to one method of carrying out this invention, as diagrammatically indicated in the accompanying drawing, there is 35 situated at the front of the aeroplane or at any other convenient point, an automatic control-stick A supported at B by a universal joint. At the top of the control-stick 40 is a four-way vane C having two of its blades c^1 c^2 set parallel with the line of the wings indicated at D, and its two other blades c^3 c^4 set at right-angles to the line of the wings. The stick A extends down below the universal 45 joint B and is there connected to four springs E E^1 and F F^1 respectively, whereof the springs E E^1 are in line with the blades c^3 c^4 and the springs F F^1 in line with the blades c^1 c^2 . The springs are in tension and 50 the spring E is connected by a flexible line or cable E² to a roller E³, and the springs F F^1 are similarly connected to rollers F² and F³ respectively.

Below the universal joint, the stick has 55 operative connection by a cable E⁴ with the elevator, not shown in the drawing. This

cable extends backward from the stick in the direction of movement of the aeroplane, so that backward movement of the stick will give a direct pull upon it and thus raise the 60 elevator. Another cable E⁵ extends from the back of the stick above the joint B and is also connected to the elevator in such manner that when it is pulled upon it will depress the same. The stick is also connected by cables 65 F⁴ F⁵ to the ailerons. These cables extend out from opposite sides of the stick and at right-angles to the cable E⁴, the cable F⁴ being connected to the aileron on that side of the stick, and the cable F⁵ to the aileron on 70 its side of the stick; the ailerons are not shown in the drawing.

The operation of this device is as follows:

It will be seen from the above that the 75 effect of this stabilizer, if left to itself, is to cause the machine to always travel at a constant speed, which if the engine-power is in-excess of that which is required for traveling on the level (and this normally would 80 be the case) will be at a climbing angle. To reduce this angle therefore, or to fly level, or to descend, the pilot, unless he changes the angle by his own control-stick, will do so by throttling the engine or by adjustment 85 of the tension of the stabilizer-springs, which will of course change his speed of flight.

If the machine is to fly on a level straight course, the springs E E^1 and F F^1 are so 90 tensioned that the stick A is kept in an approximately vertical position when the machine is traveling at a given speed. It results, therefore, that if the nose of the machine should rise, the speed will decrease and 95 the wind-pressure on the blades c^1 c^2 of the four-way vane C will thus be decreased. This will upset the balance of the springs and consequently the spring E will pull the stick in such direction that the upper end is 100 moved forward. This pulls upon the cable E⁵ and depresses the elevator, with the result that the machine will be again brought to the level position and its speed once more brought to the normal, so that the stick A 105 again assumes the position which it occupied when the action of the springs and the wind-pressure on it were balanced. If the machine should commence to nose-dive, the speed will increase, and thus the wind-pressure on the blades c^1 c^2 will force the top of the stick back and thus cause the cable E⁴ 110

- to be pulled upon to raise the elevator, whereby the machine is again brought to the level and the speed made normal. Similarly, should the machine side-slip to the left (as viewed by the pilot) the induced wind-pressure on the blades $c^3 c^4$ will cause the ailerons, which may be cross-connected, to be operated by the cable F^5 so as to raise the left-hand side of the machine, or if side-slip occurs in the opposite direction, the corresponding induced wind-pressure on the same blades $c^3 c^4$, but on the opposite sides, will cause the ailerons to be appropriately operated by the pull on the cable F^4 to raise the right-hand side of the machine. From the above it will be seen that when changing the course by ruddering, the machine automatically banks itself.

It will be appreciated that the arrangement shown in the drawing is entirely diagrammatic and the details can be varied as required for practical purposes. Preferably the ailerons would be cross-connected so that when one is raised the other would be lowered.

Any convenient means may be provided for rotating the drums E^3 , F^2 , F^3 , and for holding them in the position to which they are set. Preferably such means would take the form of some pawl-and-ratchet device, pedal- or lever-operated, so that each drum could be rotated step-by-step in either direction to increase or decrease the tension on the springs. Usually speaking, the rollers F^2 F^3 would not require to be moved after the first adjustment, but the roller E^3 would need to be re-adjusted whenever the normal speed of the machine was to be increased or decreased; thus if it were desired to fly at a greater speed than that for which the machine is set, the spring E would need to be tensioned up so that the increase of wind-pressure upon the blades $c^1 c^2$ would only keep the stick A in the position for level flying; automatic adjustment would then occur when the speed exceeded this higher speed for which the machine is set or dropped below it.

What I claim as my invention and desire to secure by Letters Patent is:—

1. In an aeroplane, a stabilizer comprising the combination with an automatic control-stick which is universally mounted and carries a four-way vane whereof two of the blades are located in a fore-and-aft plane and the other two are located in a transverse vertical plane at right-angles to the former plane, of a plurality of springs which are connected each at one end to the stick and at their other ends to the aeroplane, two of which springs are arranged laterally on opposite sides of the stick and tend to keep the stick upright in the said transverse plane, and a third spring is arranged in a fore-and-aft direction and tends to

keep the stick upright in the said fore-and-aft plane at a predetermined speed of the aeroplane, means for operatively connecting the stick to the elevator of the aeroplane to control the same by fore-and-aft movements, and means for operatively connecting the stick to the ailerons of the aeroplane for controlling the same by lateral movements of the stick.

2. In an aeroplane, a stabilizer comprising the combination with an automatic control-stick which is universally mounted and carries a four-way vane whereof two of the blades are located in a fore-and-aft plane and the other two are located in a transverse vertical plane at right-angles to the former plane, of two opposed lateral springs which are connected each at one end to the stick and at their other ends to the aeroplane and tend to keep the stick upright in the said fore-and-aft plane at a predetermined speed of the aeroplane, means for operatively connecting the stick to the elevator of the aeroplane to control the same by fore-and-aft movements, and means for operatively connecting the stick to the ailerons of the aeroplane for controlling the same by lateral movements of the stick.

3. In an aeroplane, a stabilizer comprising the combination with an automatic control-stick which is universally mounted and carries a four-way vane whereof two of the blades are located in a fore-and-aft plane and the other two are located in a transverse vertical plane at right angles to the former plane, of a plurality of springs which are connected each at one end to the stick, two of which springs are connected at their other ends to the aeroplane, and are arranged laterally on opposite sides of the stick and tend to keep the stick upright in the said transverse plane, a tension-regulating device having one end connected to the aeroplane and its other end connected to the other end of a third spring which is arranged in a fore-and-aft direction and tends to keep the stick upright in the said fore-and-aft plane at a predetermined speed of the aeroplane, means for operatively connecting the stick to the elevator of the aeroplane to control the same by fore-and-aft movements, and means for operatively connecting the stick to the ailerons of the aeroplane for controlling the same by lateral movements of the stick.

4. In an aeroplane, a stabilizer comprising the combination with an automatic control-stick which is universally mounted and carries a four-way vane whereof two of the blades are located in a fore-and-aft plane

and the other two are located in a transverse vertical plane at right-angles to the former plane, of two opposed lateral springs which are connected each at one end to the stick, two tension-regulating devices connecting each the other end of one of said springs to the aeroplane, two opposed fore-and-aft springs which are connected each at one end to the stick, and whereof one is connected at its other end to the aeroplane, a third tension-regulating device connecting

the other end of the other fore-and-aft spring to the aeroplane, means for operatively connecting the stick to the elevator of the aeroplane to control the same by fore-and-aft movements, and means for operatively connecting the stick to the ailerons of the aeroplane for controlling the same by lateral movements of the stick. 15

In testimony whereof I affix my signature. 20

THOMAS JAMES TAPLIN, JR.
